UNITED STATES PATENT OFFICE.

CHARLES H. KILLOUGH, OF WICHITA, KANSAS.

WIND-MOTOR.

1,359,605.

Specification of Letters Patent. Patented Nov. 23, 1920.

Application filed May 27, 1920. Serial No. 384,644.

To all whom it may concern:

Be it known that I, CHARLES H. KILLOUGH, a citizen of the United States, and a resident of Wichita, in the county of Sedgwick and 5 State of Kansas, have invented certain new and useful Improvements in Wind-Motors, of which the following is a specification.

My invention relates to wind motors—formerly called windmills—and has for its 10 general object to provide a wind-motor adapted for the driving of light machinery of any kind by direct rotary motion. Standard windmill construction is unable to do this kind of driving as it only provides for 15 reciprocating a pitman.

The invention consists, first, in means for driving one or more countershafts continuously; second, in means for holding the head (or motor proper) against rotating in 20 a horizontal plane except when the direction of the wind is changing; third, in automatic means permitting the head to turn during such intervals; fourth, in means for conveniently stopping the motor while the 25 wind is blowing; and further, in certain minor features of construction and operation, all of which are hereinafter set forth.

In the accompanying drawings, Figure 1 is a partial elevation of a motor embodying 30 the improvements, many parts being shown in section; Fig. 2, a sectional elevation of gearing at the base of the motor; Fig. 3, a detail of a cam and roller, viewed on line A—A of Fig. 1; Fig. 4, a horizontal sectional detail viewed on line B—B of Fig. 1; Fig. 5, a detail view in elevation, showing certain parts seen on Fig. 1; Fig. 6, a plan view of means for controlling the vane; Fig. 7, a detail of guides for a deflecting- 40 cable; Fig. 8, a detail viewed in section on line C—C of Fig. 1; Fig. 9, a plan view of the cam shown in Fig. 3.

The wind-wheel 1 and the vane are of ordinary or any preferred construction. 45 The tower 3 may be of ordinary construction excepting as hereinafter noted. The legs 3 of the tower are joined at their upper ends to a ring 4 provided with a race for a ball-bearing 5, on which the head frame 50 casting is rotatably mounted. This casting

comprises the lower and upper parts 6, 7 which together form a closed housing when handhole-plate 8 is on. In the housing are split bearings 9, 10 for the wind-wheel shaft 12.

Rotation of the wind-wheel is transmitted as follows: through shaft 12, bevel pinions 13, 14, 15 to a bevel gear wheel 16, through a vertical shaft 17 which extends downward to a point near the ground—through bevel gear 18 to bevel gears 19, 20, which drive two countershafts 21, 22.

Bevel pinions 13, 14 are each keyed or pinned on shaft 12. The intermediate bevel pinion 15 is provided with an integral spur gear 23 which drives a spur gear 24 integral with bevel gear 16, which is keyed on shaft 17. This gear arrangement offsets the greater wear of shaft bearings that would result from the use of but one drive 70 pinion.

Equal wear and driving mesh of this gearing is promoted by the torsion of a spring 25 which is so clearly shown that a description of its effect is unnecessary.

The gearing described may be run in oil. Oil may enter and fill the tube 26, but cannot pass below a packing 27, having a gland 28. Shaft bearing 10 also has a packed gland 29.

The bottom bearing 30 of shaft 17 is formed in a pedestal 31. The weight of said shaft is supported through the medium of its upper and lower gears 16, 18, both keyed thereon. The hub of gear 16 is 85 mounted on an annular ball-bearing 32. The face of bottom gear 18 is formed with a ball-race, turning on annular ball bearing 33 on the pedestal 31.

The vane 34, shown entire in Fig. 6, has 90 its hub lugs 35 keyed on a vertical rock-shaft 36, journaled in lugs 37, 38 on the housing 6—7. Normally, the vane is held at an angle normal to the wind-wheel by the pull of a tension-spring 39, acting on an arm 95 40 fixed on shaft 36 and being anchored to a fixed lug 41.

With the wind-wheel in operation and a load on a driven shaft as 21 or 22, there will be a tendency for the head to rotate bodily 100

upon its bearings. Such motion is of course necessary when the direction of the wind changes, but when the wind blows from one quarter, such bodily rotation must be prevented. This is accomplished by a device illustrated on Figs. 1, 3, 4 and 5. On the bottom of the lower housing part 6 is cast a depending annular flange 44. In this flange is a notch 45. Just beneath flange 10 44, an annular flange 46 is cast upon ring casting 4, and this flange is provided with a sufficient number of equally spaced notches 47. A latch-lever 48 is set in line with notch 45, said lever being pivoted on a pin 15 49 held by a lug 50 on casting 6. The inner end of said lever lies partly in notch 45 and partly in any one of the series of notches 47. On the inner arm of lever 48 is a weight 51, and on the outer end of said lever 20 is a small roller 52. When the latch formed by the inner end of the lever is held down by the weight 51, the head or housing is held against rotation. To complete the utility of the device, I further provide means 25 whereby the turning of the vane 34 on its own axis, from its normal angle, automatically releases the head and permits it to turn. Contacting the roller 52 is a cam plate 33 having its hub keyed upon the vane shaft 36. In the lower face of the cam plate is 30 a central recess 54 formed with inclined approaches. Normally, the weight 51 holds the roller 52 up in said recess (when the vane's angle is normal). Whenever the 35 vane is deflected, either manually or by the wind, the rocking of shaft 36 will turn the cam plate far enough to force its roller downward a sufficient distance to lift the latch end of lever 48 out of a lower notch. 40 As soon as lateral pressure upon the vane ceases, the spring 39 will restore the vane to normal angle, bringing the cam recess 54 to center, whereupon the latch end of lever 48 will drop into the first notch it encounters, thereby latching the head to the tower 45 as aforesaid.

In the drawing I have shown the following construction of means for stopping the wind-wheel while the wind is blowing by turning the vane through an angle of ninety degrees, the effect of which is well known. It is to be understood however that any equivalent means for deflecting the vane 50 may be employed, and I do not limit my claim to the following mechanism.

A second crank-arm, 55, is keyed on vane-shaft 36, or it may be integral with arm 40 as shown. The normal angles of said arms are shown on Fig. 6. The operating cable 60 56 is connected to arm 55 as shown, passes over grooved guide-rollers 57, 58, 59 down through the center of the hollow shaft 17 and supports a short depending rod 60 having a nut 61 on its lower end. Supported 65 by this nut is a small annular ball bearing

62, upon the upper half of which rests a crosshead 63 comprising a pair of oppositely directed lugs 63' passing slidably through vertical slots 64 in the shaft. Mounted on lugs 63' are a pair of anti-friction rollers 65, which support a non-rotary ring 66, connected pivotally by pins 67 to a yoke 68, formed intermediate the ends of a lever 69, fulcrumed at about the point *f* to a member of the tower. Motion 70 is communicated to this lever directly or through a pull-cord 70. By drawing this down the cable 56 is drawn down when it is desired to stop the motor, this being effected by deflecting the vane as aforesaid. The 75 cord 70 is to be tied down until the operation of the motor is again desired. The rotation of the vertical shaft 17 will of course rotate the crosshead 63, but this will not place any strain nor wear upon the 80 lever-actuated parts above mentioned.

It will thus be apparent that my invention provides a practical wind-motor by which light machinery may be driven by 85 continuous rotation.

By the term "head" in the claims I mean to designate the rotatable housing and the various bearings forming parts thereof.

Having now described my invention, what 90 I claim and desire to secure by Letters Patent is:

1. In a wind-motor, a tower, a head rotatably mounted on the tower, a rockable vane and a wind-wheel mounted on said head, means governed by the angle of the 100 vane, normally preventing rotation of the head, and means to return the vane to a normal angle.

2. In a wind-motor, a head rotatably mounted on a tower, a rockable vane and a 105 wind-wheel mounted on said head, means governed by the angle of the vane, normally preventing rotation of the head, said means also being adapted to permit the head to be adjusted by action of wind upon the vane. 110

3. In a wind-motor, a tower, a head rotatably mounted on the tower, a rockable vane and a wind-wheel on the head, a movable latch operating between the head and the 115 top of the tower, a rock-shaft on which the vane is mounted, and means operable by said rock-shaft controlling the position of said latch.

4. In a wind-motor, a tower, a head rotatably mounted thereon, a wind-wheel and a rockable vane mounted on the head, a notched ring held by the top of the tower, a correspondingly notched ring carried by the head, both rings being concentric with the axis of the head, a latch taking into any 120 pair of notches and releasable from the notch in one ring, said latch being carried by the head; and means controlled by the angle of the vane relative to the head, governing the position of said latch. 125

5. In a wind-motor, a rockable vertical shaft, a vane fixedly mounted thereon, a spring normally holding the vane at the normal angle to a wind-wheel, a cam carried by said shaft, a latch lever actuatable by said cam, and means whereby said latch lever normally prevents rotation of the

frame upon which the wind-wheel is carried but permits such rotation when the vane is deflected upon its axis.

CHARLES H. KILLOUGH.
